Patented July 2, 1918.

UNITED STATES PATENT OFFICE.

HOWARD J. FERRIS, OF HARVARD, ILLINOIS, ASSIGNOR TO HUNT, HELM, FERRIS & COMPANY, OF HARVARD, ILLINOIS, A CORPORATION OF ILLINOIS.

OVERHEAD TRACK.

1,271,454.

Specification of Letters Patent.

Patented July 2, 1918.

Application filed May 2, 1918. Serial No. 232,074.

To all whom it may concern:

Be it known that I, HOWARD J. FERRIS, a citizen of the United States, residing at Harvard, in the county of McHenry and State 5 of Illinois, have invented a new and useful Improvement in Overhead Tracks, of which the following is a specification.

My invention relates to certain new and useful improvements in overhead tracks and 10 is fully described and explained in the specification and shown in the accompanying drawings, in which:—

Figure 1 is a side elevation showing the essential features of my improved device; 15 Fig. 2 is a horizontal section on the line 2 of Fig. 1; Fig. 3 is a bottom plan of the parts shown in Fig. 2; Fig. 4 is a bottom plan with the bottom plate removed; Fig. 5 is a side elevation of the right-hand end 20 of the coupling member with the track shown in vertical section, the view being similar to the right-hand portion in Fig. 1 with this exception; and Fig. 6 is a transverse section on the line 6.

25 Referring further to the drawings, 7 is a rigid track which, in the form here illustrated, has one flat wall, the edges being recurved at top and bottom to leave between them a slotted opposite wall. The end of 30 this track fits over a reduced end 8 on the coupling member hereinafter described in greater detail. A nut 9 is laid in the slot of 35 the track and thereby held against rotation and is engaged by a screw 10 passed through the end of the track whereby to hold the track firmly on the reduced end of the coupling member.

The coupling member is provided with a bracket 11 of substantial construction adapt- 40 ed to be secured to one of the beams of the building. Carried by this bracket, and pref- erably attached by bolts 12, is a plate 13 provided on one side with a rib 14 in line with the rigid track, the reduced end 8 being 45 a shouldered extension of this rib, and the reduction being such that the upper surface of the rib and the rigid track fall in line. The rib slants down at its forward end at 50 15 and is hollowed out underneath so as to receive the end of a flexible track 16, pref- erably of round rod. The groove in the 55 lower part of the rib 15 extends back throughout practically the whole length of the plate 13 and is then recurved to one side and back to the front in a horizontal plane

so that the end of the flexible track may be bent into hook form and lie in the groove as shown in Fig. 4.

The flexible track is held in place within the groove in the plate of the coupling mem- 60 ber by a bottom plate 17 of the form shown in Fig. 3, the bottom plate in the form here illustrated having upturned ears 18 to en- gage and depress the fingers which are pro- 65 vided upon certain types of litter carriers for the purpose of safely holding the wheels upon the track. The present structure af- fords a peculiarly simple and desirable ar- 70 rangement, whereby a rigid track may be combined with a flexible track in substan- tially the same line. The litter carrier run- 75 ning upon the flexible track rides up on the rib of the coupling member and thence to the rigid track, thus rising above the plane of the end of the rigid track which can be 80 recurred underneath the level of the rigid track and of the rib, whereby to secure the firm support which is requisite in structures of this character.

I realize that considerable variation is pos- 85 sible in the details of this construction with- out departing from the spirit of my inven- 90 tion; therefore I do not intend to limit my- self to the specific form herein shown and described except as pointed out in the fol- 95 lowing claims, in which it is my intention to claim all the novelty inherent in the con- struction as broadly as is permitted by the state of the art.

What I claim as new and desire to secure 90 by Letters Patent, is:—

1. In combination, a flexible track and a rigid track lying in the same vertical plane, and an intermediate coupling member hav- 95 ing a rib connecting the flexible and rigid tracks and having a recess beneath the rib, the end of the flexible track being recurred laterally beneath the rib in a horizontal plane and held in said recess.

2. In combination, a flexible track and a rigid track in the same vertical plane, the rigid track being slightly above the flexible track, a coupling member having a rib run- 100 ning down from the rigid track to the flexi- 105 ble track, the end of the flexible track being brought in under the rib and recurred in a horizontal plane.

3. In combination, a flexible track and a rigid track in the same vertical plane, the rigid track being slightly above the flexible 110

track, means forming an inclined track-way running down from the rigid track to the flexible track, and means in the horizontal plane of the flexible track and beneath said track-way for securing the end of the flexible track in position.

4. In combination, a flexible track and a rigid track in the same vertical plane and

a coupling member having a track-way connecting them, the free end of the flexible track being recurved to form a hook in a plane beneath said track-way, whereby a carrier running from the flexible track to the rigid track passes above the recurved hook end of the flexible track.

HOWARD J. FERRIS.
